UNITED STATES PATENT OFFICE.

CLARENCE W. WHEELER, OF CHICAGO, ILLINOIS.

AUTOMATIC ELEVATOR-DOOR LOCK.

1,262,726.

Specification of Letters Patent. Patented Apr. 16, 1918.

Application filed May 21, 1915. Serial No. 29,694.

To all whom it may concern:

Be it known that I, CLARENCE W. WHEELER, a citizen of the United States, residing at Chicago, in the county of Cook and State of Illinois, have invented a new and useful Automatic Elevator-Door Lock, of which the following is a specification.

My invention relates generally to locks for the hatchway doors or gates of elevators, but particularly to locks for the doors or gates of automatic electric passenger elevators of the push-button-control type.

The objects of my invention are (1) to enable the operator, either from the hallway or as a passenger in the elevator car, by pushing a button, to select the door or gate which alone, of the gates opening into the hatchway, shall be openable at the end of a given trip; (2) to render all gates unopenable from either within or without the car, except when the latter is at one of the landings, and then only the gate at that particular landing; (3) to render it impossible for the car to leave, or be moved away, from any landing, unless the gate or door at that landing is not only closed but also locked.

I attain these objects by a mechanism illustrated in the accompanying drawings, in which Figure 1 is a side elevation of the device as it appears from without when in a locked and quiescent state. Fig. 2 is a view from the same point, with the cam-lever and the near wall of the containing box removed. Fig. 3 is a front elevation of the same as Fig. 1, but with the near wall of the box removed. Fig. 4 is a side elevation with the near wall of the box removed, but the cam-lever replaced, and showing the position of the parts after the magnet has been energized, but before the car has arrived at the landing where this particular lock is located. Fig. 5 is a view of the same after the car has arrived at the landing and come to a stop, but before the gate has been opened. Fig. 6 is a view of the cam-lever from the side next the box. Fig. 7, Sheet two, is a diagrammatic illustration of the relative positions of the locks, doors and switches, also of the car, the floor control and part of the wiring. Fig. 8, Sheet three, is a continuation and amplification of Fig. 7, diagrammatically showing the motor control, its wiring, and the wiring of the motor and brake. While Fig. 9, Sheet four, shows the floor control in front elevation, with the wiring of its switch-board

in diagram. The same reference characters refer to the same parts throughout the several views.

The car-cam A, the box B, with its attachments and contents, and the gate-hook C, constitute the main, larger and severable divisions of the device. Of these, the first, or car-cam A, is an ordinary doubly-inclined plane, consisting of a strip or wedge with a non-inclined middle portion and rigidly fastened to the outside of the car, preferably near the top; the last, or gate-hook or latch C, is of a goose-head shape, and rigidly fastened to the door or gate in a position corresponding to that of the cam on the car; while the box B, which is the framework of the lock proper, is rigidly fastened to the jamb of the door, or the wall of the elevator shaft in a corresponding position, and so as to be out of ordinary reach.

The contents and attachments of this box or frame B, consist of a casting comprising a hollow cylindrical or tubular trunk D, arms E and F, the latter terminating in a cam I, and the hook or catch K, all projecting therefrom and being part thereof. This casting is pivotally mounted, through its trunk, on a stationary shaft or rod, rigidly anchored to and extending from the far wall of the box through the near wall thereof, and terminating in the stop P. Pivotally mounted at the extremities of the arms E and F, is the rod or shaft R, having rigidly fastened thereto, at or near the middle point, and between the arms E and F, the slotted lever L, and, at its near or outer end, which extends, via a slotted opening, through the front wall of the box, the cam-lever M, having a V-shaped slot T, extending about half-way through, in its side next the box, and a roller pivotally mounted between jaws at its free end. Back of this casting, and parallel with the front wall of the box and attached at one end to the floor thereof by means of a hinge joint, is a strap V, with a cam-pin or catch N at the other end projecting at right angles therefrom and passing loosely through a hole in the front wall, so as to engage the cam-lever M where it is held in position by a spring S which permits it to be tilted back on engaging said lever, when same is drawn into horizontal position.

Rigidly mounted within the upper part of the box or frame, is a coil or helix of insulated wire Z, loosely surrounding the upper

end of a movable soft iron core, piston, or plunger X, while the other end is pivotally connected, through its slot, with the lever L, the pivot extending backward and terminating in a metal ferrule U, insulated therefrom, for opening and closing a switch Y, mounted on the back wall of the box. Near this switch Y, and parallel therewith and also mounted on the back wall of the box, is the switch W, open only when the car is at that landing and the device is unlocked.

Referring to Fig. 7, Sheet two, Q are switches in series with switches W and Y, 15 and mounted, as are the locks, on the door-jambs, or wall of the hatchway adjacent to the doors, so that they will be closed by cams on the doors when the latter are closed, and open when they are opened. H are 20 the hallway push-buttons and switches; O is the box, frame or casing in the car mounting the car push-buttons for the various floors, and also the notch-held hall-button-cut-out switch, J, pivoted at the points j 25 and k; while G is the emergency switch and push-button in the car for breaking the circuit and stopping the car at any necessary or desired time or point.

The floor control, diagrammatically shown 30 in Fig. 7, and shown in front elevation, with wiring in diagram, in Fig. 9, is a standard Anderson device, and consists of a series of iron wheels, and pairs of wheels, d, du, and u, with part of their fellies or rims cut 35 away, and rigidly mounted at their hubs on a shaft, b, which, in turn, is pivotally mounted in a frame, a, and which, via reduction cog-wheels, c, mechanically communicates and co-operates with the car, drum 40 or drive-sheave, so as to cause said shaft, with the said wheels mounted thereon, to make one and only one complete turn pending the passage of the car from end to end of the hatchway, it being observed that 45 there is but a single such wheel at each end of the device, with an appropriate gap, as shown between the dotted lines, to break the circuit and stop the car upon the latter's arrival at the corresponding extreme landing, and as many pairs of wheels as there 50 are intermediate landings, the lengths of the part-rims being proportional to the distances of said intermediate landings respectively from the extreme landings, and having appropriate gaps between them to break the circuit and stop the car upon its arrival at said intermediate landings respectively. On the inner side of these wheels, and, in 55 case of the pairs, between them, and closely adjacent to their said rims, or part-rims, are the solenoids, e, mounted on shelves, n, supported by standards, f; while pivotally mounted in the upper ends of their cores are the tilting armatures, m, terminating in the 60 fingers, t, which communicate and co-oper-

ate with the switches, i, mounted hinge-fashion on the pivots, p, p', p'' and p''', on the switch-board at the top of the said frame, and which are held in open position by the relatively light springs, r. It will 70 be observed that, when a current of electricity passes through any one of said solenoids, as, according to the illustration, the one at the second floor, a magnetic field will be created or induced thereabout 75 embracing the adjacent part-rim, d, magnetizing it, and drawing the near end of the armature, m, down upon it, thus tilting the finger, t, over against the switch, i, and closing it; and that this position of these parts 80 will be maintained until the contact between said rim and armature is broken by the passing of said rim from thereunder at its end, m', by reason of the rotation of said system of wheels. It will be observed 85 further that a corresponding thing would have happened had a contact been established between any other of the rims, or part-rims, and its corresponding armature.

To understand the operation of this invention, assume an automatic elevator serving several floors, say four, as in the illustrations, with a door locked or capable of being locked by a unit of this device at each of them; that the car is at one of the upper floors, say the third, as shown in Figs. 7 and 9; and that it is desired by someone on that floor to descend via the car to, say the second floor, as is also shown in Figs. 7 and 9.

The door at the third floor being unlocked, as shown in Fig. 5, and at that floor in Fig. 7, it is possible to open it and enter the car. This done, the passenger or operator closes the door, being careful to do 105 so completely, so as to close the switch, Q, at that floor, and also enable the hooks, K and C, to engage each other when the cam-lever, M, is released by the departure of the car. He then presses the push-button corresponding to the second floor (the act illustrated in 110 Figs. 7 and 9 as being in process of performance), and this, by means of its extreme inner end, engages the apron of the pivoted switch, J, normally closed when the 115 car is not in use, and opens it, thus disconnecting line 9 from line 8, and cutting out all interference from any of the hall buttons and switches, and by means of the switch 2', connects line 12 with line 8. This 120 operation establishes a circuit through the second-floor solenoid, e, from one side of "the line" via the upper fuse (Fig. 8), the line 6, the emergency switch G, (Fig. 7), and lines 7, 8, 12, 10 and 5, through the 125 switches, Q, W and Y at the various floors and locks (Fig. 7), and thence still via 5 and the lower fuse to the other side of "the line", thus delivering current to said solenoid, closing the switch, i, at d', and con- 130

necting line 7 with line 2, and also, via the pivot, p' , with line 12.

As the pressure on the push-button is designed to be, and usually is but momentary (though it would do no harm, and make no practical difference, should it continue throughout the trip), part of this circuit is but temporary, line 12, from said push-button to its first division point, z , 10 and line 8, as well as line 7 from the motor control (Fig. 8) to the point, z , being "dead," or superfluous for the balance of the trip, for which the circuit is electro-magnetically maintained, and will continue to be, by said 15 solenoid, until, by rotation upward of the part-wheels of the floor control, the end, n' , of the part-rim, d , slides from under its armature, m , the circuit now being the upper fuse, 6, 7, i , p' , 12, 10, 5 as above, 20 and the lower fuse.

Meantime, by reason of the closing of the switch, i , at d'' , current will also be flowing to the "down magnet" of the motor control, (Fig. 8), the circuit being the upper 25 fuse, line 6, the emergency switch G, line 7, the switch i , line 2, a "low-limit switch," normally closed, the "down magnet," line 4, the other "low-limit switch," 10 to the point y , 5 through the switches Q, W and Y at 30 the various floors and locks and the lower fuse. The "down magnet" being energized, contacts will be produced at the points, D' , D'' , and D''' , (Fig. 8), connecting "the line" with the "stator of the motor" and 35 also, at the lower points, D' and D''' , via the lower points, U' and U'' , (Fig. 8), with lines 15 and 16 and the "brake," releasing the latter, and setting the motor in motion, and maintaining them so pending the trip, 40 or until the circuit is broken at d'' by the sliding of the end m' from under its armature, m , (Fig. 9).

Meanwhile, moreover, current will also be flowing to the coil or lock magnet Z, at 45 the second floor, the circuit being the upper fuse, line 6, the emergency switch G, line 7, switch i , pivot p' line 12 via z through the coil, Z, at the second floor, line 5 through the switches, Q, W and Y, at the various 50 floors and locks, and the lower fuse.

It will be observed that this current will energize said lock magnet, drawing its core, piston or plunger X, up into it, and, by means of the slotted lever, L, and the shaft, 55 R, lifting the cam-lever, M, into horizontal position, where it is held by means of the catch pin, N, sprung into the cam slot, T, by the spring, S; and at the same time, by means of the ferrule, U, closing the switch, 60 Y, as shown in Figs. 4 and 7, while the car proceeds on its way from the third to the second floor.

As the car approaches the second floor, and its floor is within approximately half 65 the length of the car cam, A, of flush there-

with, said cam quietly and gently engages the free end of the cam-lever, M, through the medium of its roller, and pushes it over in the direction of the lock, thus tilting the casting, D, with its extensions, forward, disengaging the hooks, K and C, and by means of the same operation, opening the switch, W, as shown in Figs. 5 and 7, whereupon the car will stop, floors flush, though not by reason of the opening of the switch, W, 70 for the switch, Y, in multiple therewith, is closed, but by reason of the circuit's having been broken at the end, m' , of d , of the "floor control," Fig. 9.

Meantime, it will have been observed 80 further that, as the car moved away from the third floor, the cam, A, disengaged the cam-lever, M, at that floor, and, there being no longer any current through the coil, Z, of the lock magnet at that floor, said cam-lever gently slid off the catch-pin, N, via the open end of its V-shaped slot, T, thus causing the hooks, K and C, at that floor, to engage each other, locking the door, and at the same time allowing the switch, W, at 90 that floor to close.

The car having arrived at the second floor, and its door being unlocked, as above described, it will be possible to open the door, which being done, opens the second-floor switch, Q; and so long as this door and switch remain open, it will be impossible, from any of the push-buttons, either in the car or in any of the halls, to get current to start the motor, or move the car 100 away from this landing.

When, however, the door is completely closed again, from either within or without the car, thus again closing said switch, Q, current can again be procured and the car 105 moved by pressing any one of the hall or car floor buttons, except those corresponding to the second floor, where the car is. But the car will not move more than approximately half the length of the non-inclined portion of the car-cam, A, unless the hooks, K and C, are completely engaged, and the door firmly locked. For if, by reason of any disorder, when the cam, A, in moving up or down, releases the cam-lever, M, and the latter drops into quiescent position, thus opening the switch, Y, the casting, D, with its extensions, should not tilt back quite far enough to securely engage the hooks, K and C, the cam, I, 110 will not allow the switch, W, to close, and there will again be no current to move the car until the disorder has been remedied.

This last, it will be further observed, is a measure of safety, and intended to provide 115 against the contingency of the device's being out of order, or otherwise failing to operate. But to guard as much as possible against the occurrence of such a contingency, a spring of suitable strength is mounted 120

under the hook, K, to coöperate with it, and impel it into secure engagement with the hook, C.

From a further examination of the drawings, and particularly of the wiring (Figs. 7 and 8) it will be observed generally that, had the car been at any other landing, or had it been desired to go, or to call the car to any other floor, the behavior of the device would have been correspondingly the same, the only difference being in parts of the circuits. Had it been desired, for example, to go to the first floor instead of the second, line 11 would have been called into play instead of line 12. Or had it been desired to go to the fourth floor, line 14 would have been utilized instead of 12, and lines 1 and 3, instead of 2 and 4 respectively. And had it been desired to call the car to any other floor from the hallway push-buttons, line 9 would have been called into action instead of those parts of lines 11, 12 or 14 between the car buttons and their nearest division points, z and e' respectively. 25 And so of line 13, had the car been at any other floor than the third.

It is, of course, possible to resort to modifications and variations in the construction of this device, but in so far as they do or shall not materially or substantially depart from the scope, spirit and principle of this invention, they are hereby expressly included therein.

Having thus described my invention, I claim:

1. A lock for elevator hatchway doors comprising a latch on the door, a casing on the door-jamb, a catch to engage the latch when the door is closed, a lever for disengaging the catch, an electro-magnet for shifting the lever, a catch-pin to engage the lever, a cam on the car to operate the lever, a switch arranged to be closed when the lever is shifted, and a second switch arranged to be opened when the lever is operated.

2. A control lock for elevator hatchway doors comprising a latch on the door, a catch in the casing to engage the latch when the door is closed, a cam-lever for disengaging the catch normally resting in an inoperative position, an electro-magnet to shift the cam-lever to operative position, a catch-pin to engage and hold the cam-lever in opera-

tive position, a cam on the car to operate the cam-lever, a switch arranged to be closed when the cam-lever is shifted to operative position, and a second switch arranged to be opened when the cam-lever is operated by the cam on the car.

3. A control lock for elevator hatchway doors comprising a latch on the door, a casing on the door-jamb, a pivoted catch in the casing adapted to engage the latch when the door is closed, a pivoted cam-lever on the casing for disengaging the catch and normally resting in an inoperative position, a push-button-controlled electro-magnet in the casing for shifting the cam-lever into operative position, a spring-stressed catch-pin to engage and hold the cam-lever in operative position, a cam on the car to operate the cam-lever, a control-switch arranged to be closed when the cam-lever is shifted to operative position, and a second control switch arranged to be opened when the cam-lever is operated by the cam on the car.

4. An automatic control lock for hatchway doors of automatic elevators of the push-button-control type, comprising a rigid latch on the door, a casing rigidly mounted on the door-jamb, a spring-actuated pivoted catch in the casing adapted to engage the latch when the door is closed, a pivoted cam-lever outside the casing for releasing the catch, same being provided with a slot and normally standing in an inoperative position, a push-button-controlled electro-magnet in the casing adapted to shift the cam-lever to operative position, a spring-stressed catch-pin through the wall of the casing adapted to coöperate with the slot to engage and hold the cam-lever in operative position, a rigid cam on the car adapted to operate the cam-lever, a control switch in the casing arranged to be closed when the electro-magnet is energized and the cam-lever is shifted to operative position, and a second control switch also in the casing and in multiple with said former switch and arranged to be opened when the cam-lever is operated by the cam on the car.

CLARENCE W. WHEELER.
